UNITED STATES PATENT OFFICE.

EDWARD HARTMAN, SR., OF DOVER, NEW JERSEY.

BROOM HOLDER.

Application filed December 28, 1921. Serial No. 525,377.

To all whom it may concern:

Be it known that I, EDWARD HARTMAN, Sr., a citizen of the United States, and a resident of Dover, in the county of Morris 5 and State of New Jersey, have invented a new and Improved Broom Holder, of which the following is a description.

My invention relates to a holder adapted to be applied to a wall or the like and to 10 yieldingly receive the handle of a broom or the like for holding the broom or similar article suspended against the wall.

The general object of my invention is to provide in connection with the holder a 15 handle displacing device against which the handle may be moved to assist in the ready disengagement of the handle from the holder.

Reference is to be had to the accompanying drawing forming a part of this specification in which

The figure shows a perspective view of my improved holder and its mode of functioning, it being understood that the drawing 25 is merely illustrative of one example of a practical embodiment of my invention.

In carrying out my invention in practice, wire is preferably employed in the formation of the holder and said holder is made 30 to embody a suitable vertical frame or base 10 for attaching to a wall A or the like, said frame being here shown as presenting side arms having at the upper end eyes 11 to receive fastening screws B. Advantageously, the sides are made convergent to receive 35 at the angle thereof a further fastening screw B' below which the sides are brought together as at 12 and formed at their extremities into an upturned hook 13 available 40 for hanging thereon different kitchen articles. The holder embodies a forwardly extending clamp shank 14 advantageously formed by twisting the wire together adjacent to the free ends, said free ends at the 45 front of the shank 14 being given the form of flaring yielding jaws 15 for frictionally engaging a handle such as C, the terminals of which jaws are formed into eyes 15^a or given an equivalent rounded formation.

50 A handle-displacing device 16 is provided,

which preferably also is formed of wire to present upright side members rising from the frame 10, the side members extending forwardly as at 17 above the jaws 15 and the material being continued to form a 55 front transverse bar member 18 integral with the forwardly extending side members 17. The handle-displacing device 16 may, as shown, be formed of a separate wire looped as at 20 about laterally disposed rear 60 members 19 extending between the eyes 11 and the shank 14 of the clamp.

With the described construction the device having been secured to the wall or the like, a handle C, such as a broom handle, 65 may be pressed between the jaws 15 of the clamp to be frictionally held thereby. When it is desired to withdraw the handle from the clamp the handle is grasped below the clamp and rocked forwardly so that it 70 bears against the front bar 18 of the displacing device 16 and as the handle is swung outwardly said cross bar 18 acts as a fulcrum for the handle and thus the latter may be removed from the clamp with facility 75 and with slight force exerted with one hand.

I would state in conclusion that while the illustrated example constitutes a practical embodiment of my invention, I do not limit myself strictly to the actual details 80 herein illustrated, since manifestly the same can be considerably varied without departure from the spirit of the invention is defined in the appended claim.

Having thus described my invention, I 85 claim:—

A holder for a handle of a broom or the like, having means to secure it in position and including a clamp to hold the handle; together with a handle-displacing device 90 rising on said holder above said clamp presenting side members extending forwardly at their upper ends and united by a transverse front member disposed above and rearward of the front end of the clamp 95 against which member a broom handle may bear for displacing the handle by grasping it below the clamp.

EDWARD HARTMAN, SR.
